UNITED STATES PATENT OFFICE.

JOHN N. WHITEHOUSE, OF NEW YORK, N. Y.

APPARATUS FOR FORMING ARTICLES FROM WOOD POWDER AND THE LIKE.

Application filed November 18, 1920. Serial No. 424,990.

To all whom it may concern:

Be it known that I, JOHN N. WHITEHOUSE, a citizen of the United States, residing at New York, in the county of New York and 5 State of New York, have invented certain new and useful Improvements in Apparatus for Forming Articles from Wood Powder and the like, of which the following is a specification.

10 My present invention relates to apparatus for molding cigar holder cases, pipe cases and similar articles of a hollow character.

15 The general objects of the invention are to provide a mold of relatively simple construction and one which will be entirely practical and efficient for the purposes intended.

20 A special object is to provide satisfactory apparatus for molding articles out of a wood powder mixture, such as disclosed in my co-pending application Serial No. 379,252.

25 The invention involves numerous novel features of construction, combinations and relations of parts, out of which will be disclosed in the course of the following specification which is to be read in conjunction with the accompanying drawings wherein I have illustrated a concrete and practical embodiment of the invention.

30 In the drawings referred to, Figure 1 is a perspective view of the complete apparatus, parts being indicated as broken away, for lack of space; Figures 2 and 3 are enlarged cross sectional views of the mold proper

35 showing the same in two different positions; Figures 4 and 5 are fragmentary sectional views on a further enlarged scale illustrating the operation of the mold parts; Figure 6 is another fragmentary sectional view illustrating particularly the manner in which a hinge part may be positioned on the mold; Figure 7 is a sectional view of the mold, taken on a plane at right angles to the plane of Figures 2 and 3.

40 The machine illustrated is designed for the production of cigar holder cases such as disclosed in my co-pending application referred to, and the mold therefor consists of a concave or female part 10 and a cooperating male member 11.

45 As shown in Figure 1, the convex member of the mold is supported relatively stationary on posts 12 carried by the frame 13 of the machine, and the concave member, 50 which is uppermost in this instance, is piv-

totally supported at 14 on a swinging lever 15 which is pivoted at its rearward end at 16 to a swinging link 17 pivotally connected with the frame or base of the machine at 18. The forward end of this mold lever is adapted to serve as a handle for swinging the upper mold part down over the lower mold part.

This swinging support for the upper mold member enables the same to be lifted away 65 from the lower mold part and to be swung to the rear over a suitable heating appliance such as the gas burner indicated at 19. The mold member may be supported in this rearward position over the gas burner by 70 causing the operating lever to rest on a supporting bar 20 carried by the frame.

To assist in manipulating the swinging mold part I have shown a chain 21 as hooked to the mold-operating lever at 22 and as extended up over a pulley 23, this chain being provided at its free end with a handle 23^a. It will be obvious that upon pulling on this handle the mold-carrying lever may be lifted 75 either for the purpose of swinging the mold part to the rear, or in the event where the mold part is supported at the rear, this chain may be utilized to start the lever upwardly 80 for the purpose of swinging the mold part upwardly away from its burner, the pivotal centre of the pulley 23 being located for such purposes preferably substantially in line with the pivotal support for the rear end of the lever.

In the illustration, two complete molds 90 are provided, the means for operating the same being duplicated so that one mold may be controlled independently of the other.

Also in the illustration each mold is constructed to mold two articles at one operation, the upper mold part being for the purpose provided with two mold cavities 24 receiving the cooperating projections 25 of the lower mold member.

Interposed between the two members of 100 the mold and cooperating with the lower mold member to form a cavity or cavities for the molding material, is a follower plate 26 slidingly fitting over the projecting posts 27 of the lower mold member and yieldingly 105 supported in the upraised relation shown in Figure 2 by the supporting springs 28. These springs are shown as coiled about the bolt rods 29 which slide down through openings in the lower mold member and are pro- 110

vided at the under side of the same with thumb nuts 30 forming stops adjustable to limit the upward thrust of the follower.

The stops referred to are so adjusted that when the mold is open, as indicated in Figure 2, the walls of the guiding openings, which fit over the projections 27, will form pockets about the male members of the mold to receive charges of the molding material. It will be evident that by adjusting these stop nuts the depth of these pockets or mold cavities can be varied so as to hold more or less of the molding material, as may be required by different conditions.

In use, the mold-operating lever is first thrown back to carry the upper mold element over the heater provided therefor. A charge, or charges in the case of a multiple mold, is placed in the mold cavity, this charge being melted or reduced to the required plasticity by a heater such as the burner 31 positioned beneath the lower mold member.

When the proper heat is attained the upper mold part is lifted away from the heater, the chain being usually utilized to assist this movement and the lever is swung forwardly to carry the upper mold member over the companion mold part. This upper member, by reason of this pivotal support, automatically adjusts itself to the companion part; and the proper engagement of these parts may be assisted by providing the upper part with one or more positioning pins such as I have indicated at 32 in Figure 7 to enter in corresponding guiding openings 33 in the follower plate.

As the upper mold member closes over the cavity formed by the lower member and the follower plate, the molding material indicated at 34, Figure 4, is squeezed up into the cavity formed in the upper female member, as shown in Figure 5, the follower being depressed during such operation until the position indicated in Figure 3 is reached.

To insure the proper flow of the molding material into the cavity of the female element I preferably employ means for automatically closing the mold at a gradual rate, and in accordance with the flow of the material. In the illustration this is accomplished by means of a mold-closing spring 35 shown in Figure 1 as secured at one end to the frame and as connected at the opposite end to a lever 36 pivoted to the frame at 37 and detachably connected by means of a pivoted hook link 38 with the forward end of the mold-operating lever 15. In using this device, as the mold-closing lever is swung forwardly over the lower mold element, the lever 36 is lifted by the operator against the tension of the mold-closing spring and the link 38 is swung into hooked engagement with the mold-operating lever 15 to thereby establish a connection enabling

the spring to apply its tension to the closing of the mold. This resilient force causes the molding material to flow gradually and uniformly into the mold cavity in the female member producing an outer surface for the 70 molded article having the desired finish and uniformity.

When the mold is entirely closed and the material is fully compressed and forced into the required shape the follower is preferably 75 latched in its depressed condition as by means of pivoted latches at opposite sides of the follower, one of which is indicated at 39, Figure 1, said latches being arranged to engage catch pins 40 on the lower stationary 80 mold member and being connected together by a common handle 41 which may be used for simultaneously releasing both latches. The weight of this handle is ordinarily sufficient to cause these latches to interlock 85 with the catch pins to secure the follower in its depressed condition. Hence when the upper mold element is lifted the follower remains in its depressed condition, the position indicated in Figure 3, so that the molded articles may be readily lifted off the projecting portions of the lower mold member. 90

As above stated, the apparatus is intended primarily for molding articles of a wood powder composition. This composition consists usually of a mixture of sawdust and starch with or without rosin or the like. The gradual closing of the heated mold causes this mixture to flow sufficiently to completely fill the mold cavity, and the application of heat with the mold closed changes the melted mass into a solid rigid body, substantially homogeneous throughout. When the melting and baking operations are complete the mold is opened as above described, and after removal of the products the mold is again ready for use, the interval of time required for the refilling of the mold being usually sufficient for the heating of the upper mold part which has been thrown back over the burner provided therefor at the rear of the machine. 105

Another special feature of the invention is the provision of the lower or male member of the mold with means for positioning a hinge element in the edge portion of the molded product. This feature is illustrated particularly in Figures 4, 5 and 6 and consists in the provision of the lower mold member, at the edge of the mold cavity therein, with a socket 42 to receive the angled end of a pin 43 which is engaged in the eye portion of a hinge leaf 44. This positioning pin in addition to properly locating the hinge element within the mold cavity, 110 serves also to prevent the molding material from flowing onto the eye portion of the hinge leaf. 115

When the hinge leaf is to be molded in the article the same is supported by means 120

of the positioning pin in the upstanding relation indicated in Figure 4 with the molding material packed thereabout. As the mold closes, the upward flow of the molding material swings the hinge leaf over into the inclined relation indicated in Figure 5 and causes the material to flow through the bonding opening 45 provided in the hinge leaf so that in the final molded product the hinge leaf is properly imbedded and interlocked in the edge portion of the product.

After removal from the mold the positioning pins may of course be removed from the eyes of the hinge plates to receive the proper hinge pintles.

In placing the female member of the mold at the top and causing the molding material to flow upwardly thereinto I have found that a much better finish of the exposed surface is obtained than where, as in prior instances, the female element is placed at the bottom and the molding material is initially charged thereinto. The receding plate which provides the initial mold cavity to receive the material by reason of its recession and the trapping of the same in the depressed condition, greatly facilitates the removal of the molded articles from the mold.

I claim:

1. In a mold of the character described, companion mold parts, one provided with a socket and a hinge-leaf locating pin engageable in said socket.

2. In a mold for producing a molded article with an element imbedded therein, companion mold parts, one provided between the meeting faces of the mold parts with a socket to receive the positioning pin for the imbedded element.

3. In a device of the character described, a support, companion mold parts on said support, one of said mold parts being stationary and the other movable, a lever on the movable mold part having connection with the support, a second lever pivoted to the support and having a link detachably connected to the first lever and having a spring connected to the support for exerting closing force on the first lever and thereby gradually close the mold.

4. In a device of the character described, a support, companion mold parts on said support, one of said mold parts being sta-

tionary and the other movable, a lever on the movable mold part having pivotal connection with the support, means on the support having connection with the lever for swinging said lever about its pivot to raise or lower the movable mold part, a second lever pivoted to the support and having a link detachably connected to the first lever and having a spring connected to the support for exerting closing force on the first lever and thereby gradually close the mold.

5. In a device of the character described, a support, companion mold parts on the support, one of said mold parts being stationary and the other movable, a follower between said mold parts having latch members pivotally secured thereto, said members having a handle for operating the same, pins on the stationary mold part engageable with said latch members for securing the follower to the stationary mold part in depressed condition, a lever on the movable mold part having connection with the support, a second lever pivoted to the support and having a link detachably connected to the first lever and having a spring connected to the support for exerting closing force on the first lever and thereby gradually close the mold.

6. In a device of the character described, a support, companion mold parts on said support, one of said mold parts being stationary and the other movable, a lever on the movable mold part having pivotal connection with the support, means on the support having connection with the lever for swinging said lever about its pivot to raise or lower the movable mold part, and a second lever pivoted to the support and having connection with the first lever for exerting closing force on the movable mold part when the same is in lowered position.

7. In a device of the character described, a support, companion mold parts on said support, one of said mold parts being stationary and the other movable, a lever on the movable mold part having pivotal connection with the support, and a second lever pivoted to the support and having connection with the first lever for exerting closing force on the movable mold part.

In testimony whereof I affix my signature.
JOHN N. WHITEHOUSE.
